UNITED STATES PATENT OFFICE

2,113,053

KNITTING MACHINE COMPRISING NEEDLE JACKS

Leslie Herbert Leedham and Henry Harold Holmes, Leicester, England, assignors to Wildt and Company, Limited, Leicester, England, a British company

Application July 15, 1936, Serial No. 90,660
In Great Britain August 9, 1935

5 Claims. (Cl. 66—50)

This invention consists in improvements in or relating to knitting machines comprising needle jacks which are associated with the needles and in particular is concerned with the improvement 5 of the means disclosed in United States Patent No. 1,722,989. In some circumstances, particularly in the case in which the butt ends of the needle jacks are normally sprung away from the beds of the tricks in which they are situated, 10 the action of selecting means for the needle jacks is found to tend to move the upper ends of those jacks outwardly from the tricks and this movement may be transmitted to the needles with which they are associated, to the detriment of 15 action of the latter. This is especially to be avoided when the needles are of fine gauge.

An object of the invention is to avoid this drawback and accordingly the present invention comprises the combination of sprung needle-jacks and substantially rigid means acting on the upper 20 ends thereof at least during the time at which movement of the jacks occurs, such means serving to restrain the upper ends of the jacks from moving outwardly.

Preferably, when sprung jacks are employed 25 the invention comprises the combination of sprung needle jacks and substantially rigid means acting on the upper ends thereof at least during the time at which the lower ends of the jacks are moved against the action of their springs to prevent the upper ends of the jacks from moving 30 outwardly.

Hitherto, spring bands have been employed at or near their upper ends but these spring bands 35 are found in practice to be insufficient to provide the necessary restraint for the upper ends of the needle jacks.

Preferably, the restraining means employed 40 by the present invention will be entirely rigid although when they are described as substantially rigid this term is employed to include a construction in which the restraining means may be somewhat resilient but insufficiently resilient to permit any outward movement of the upper 45 ends of the jacks.

A sprung needle jack is to be understood as a 50 jack which is either associated with an additional spring or is so formed of resilient material that the butt at its end is normally held resiliently in one position, e. g. at a position within the influence of a lifting cam, and is operable against that spring or against its own resilience into another position, e. g. into a position whereby it is not engaged by a lifting cam.

55 Moreover, a needle jack within the present

invention is not necessarily a jack that acts by direct engagement upon a needle as it may be one of a plurality of jacks through the collective medium of which the needle is actuated.

The invention is equally applicable to the case 5 of any jack combined with an instrument other than a needle, which is employed in a knitting machine and which may otherwise be dependent for its functioning, upon the springing or normal movement of the jack out from its trick.

In order that the invention may be more clearly understood a preferred example will now be described with the aid of the accompanying drawings, in which—

Figure 1 is an elevation partly in section of 15 those portions of a knitting machine necessary for the understanding of the invention, and

Figure 2 is a section on the line 2—2 of Figure 1.

Like reference numerals indicate like parts in 20 the accompanying drawings.

The invention is illustrated as applied to a circular knitting machine having a needle cylinder 10 provided with tricks 11 for needles and associated needle jacks 12, 13. For each needle there 25 will be a pair of jacks such as 12 and 13 disposed end on to one another and to their needle.

Concentric with the axis of the needle cylinder 30 is a jack presser cam 14 arranged at the upper ends of the needle jacks 13 with a depth, parallel with the axis of the machine, sufficient to maintain engagement with those upper ends during the vertical sliding movements of the jacks as they are operated to control the needle movements.

The jacks 13 have relatively rigid upper 35 portions and tail portions 130 which are of a resilient nature and normally rest in the position illustrated in Figure 1 where their lower butts 131 remain in operative relation to a raising and selecting cam 15.

Between the presser cam 14 and the needle cylinder there will be relative rotation about the axis of the machine and in the present instance it is the needle cylinder which is to be understood as rotating in company with a cylinder extension 45 16 and a base or support ring 17. The circumferential extent of cam 14, as shown in Figure 2, will be sufficient to embrace from moment to moment the jacks lying in that centre in which the vertical jack movement will occur under the 50 action for instance of cam 15.

The needle selecting means illustrated is of well known type comprising a tricked cylinder 18 having in its tricks a plurality of pattern-controlling bits 19 which operate through the inter- 55

mediary of vertically spaced presser cams 20 on butts 21 provided on swinging elements 22 of which there is one such element associated with, to lie in front of and to press against the spring end 130 of each jack 13. The pattern selection of the needles will be in accordance with the lay out of butts such as 23 on bits 19 and the lay out of the butts 21.

The invention is particularly useful in the case in which needle-selecting means and sinker-selecting means are employed, as described in U. S. patent application, Ser. No. 94,666, filed Aug. 6, 1936. This is so because in that case the sinker mechanism, which must necessarily occupy a certain vertical dimension, is disposed above the needle-selecting drum and in order to give adequate clearance between the two patterning devices extra long jacks are required. This condition is indicated in Figure 1 in which sinkers 24 are selectively controlled from a sinker patterning drum 25 formed with tricks for the reception of pattern bits 26 which control and select sinkers 24 through the medium of vertically spaced swinging cams 27 and intermediate selector elements 28. Owing to the necessity for allowing adequate space for the needle-patterning mechanism controlled from drum 18 and for the sinker-patterning mechanism controlled from drum 25, the jacks in the present example are made sufficiently long by using a main selecting jack 13 and an intermediate jack 12. By this means, the jacks 13 may be conveniently removed from the lower cylinder, whereas had the jack extended back of the needle as in United States Patent No. 1,722,989, it would not have been possible to withdraw same.

The invention is equally applicable to a fixed cylinder machine in which case the patterning mechanism as a whole will revolve around the axis of the cylinder in conformity with known practice. The invention is also applicable to flat frame or straight bar machines, necessary modifications for the application of the present invention thereto being well understood.

Alternatively, the invention may be applied to machines having any other preferred or known form of needle bed.

We claim:—

1. In or for a knitting machine, the combination of needles, sprung needle jacks having relatively resilient and non-resilient portions, pat-

tern-selecting means to cooperate with the resilient portions of the jacks, and substantially rigid means to press upon the relatively non-resilient portions at least during the time at which the resilient portions are being flexed by selection of the pattern-selecting means. 5

2. In or for a knitting machine, the combination according to claim 1 in which the relatively non-resilient portions of the jacks are situated at the upper ends thereof and the resilient portions at the lower ends, and the jacks are arranged beneath their associated needles. 10

3. In or for a knitting machine, the combination of needles, sprung needle jacks having relatively resilient and non-resilient portions, pattern-selecting means to cooperate with the resilient portions of the jacks, and rigid means comprising a cam that is moved into engagement seriatim with the needle jacks to press upon the relatively non-resilient portions at least during 20 the time at which the resilient portions are being flexed by selection of the pattern-selecting means. 15

4. A circular knitting machine comprising in combination a needle cylinder, needles and associated jacks therein, said jacks having relatively non-resilient upper portions and relatively resilient lower portions with butts projecting therefrom, pattern-selecting means to cooperate with and engage selected butts to move the lower extremities of the jacks against the resilience of 30 their lower portions, and a cam relatively rotatable with respect to the jacks about the axis of the machine to press against the upper ends of the jacks seriatim and to engage those ends during at least the time that the lower ends are being moved against their resilience. 35

5. In a knitting machine, the combination of needles, sprung needle jacks having relatively resilient and non-resilient portions, pattern selecting means to cooperate with the resilient portions of the jacks, and means relatively rotatable with respect to the jacks and movable into engagement with the needle jacks so as to press inwardly against the non-resilient portions thereof seriatim, and to engage those portions at least 40 during the time at which the resilient portions are being moved against their resilience by the pattern selecting means. 45
